UNITED STATES PATENT OFFICE

2,240,071

CANDLE BASE

Joseph Gisolfi, Brooklyn, N. Y.

Application April 1, 1940, Serial No. 327,154

3 Claims. (Cl. 67—21)

This invention relates to candle bases and, more particularly, to the bases by which the candle wicks are secured to the wax bodies of the candles.

The candle bases with which the present invention is concerned consist of flat sheet metal disks, which may be of any suitable shape, for example, circular or non-circular, such disks having an opening in which an end of the wick is secured by means of prongs struck out from the disk at said opening and extending downwardly, that is, in a direction away from the bottom of the candle when the base is attached thereto. Said prongs engage the wick therebetween whereby to prevent the movement of the wick upwardly through the candle. The downwardly projecting prongs are superior to prongs which project upwardly from the metal disk because the former more effectively secure the wick than the latter. However, the downwardly projecting prongs on the disk result in the tendency of the candle to tilt especially when the wax at the top of the candle melts during the burning of the candle. The tilting of the candle is highly objectionable because the flame of the wick can contact or move sufficiently close to the glass holder whereby to crack the same.

In accordance with the present invention, the candle bases are provided with downwardly projecting prongs for obtaining improved securement between the bases and the candle wicks and said candle bases are provided with means to prevent tilting of the candles.

The objects, features and advantages of the invention will be fully understood from the following description in connection with the accompanying drawing.

In the drawing:

Fig. 1 is a vertical sectional view of a candle provided with a base embodying the present invention;

Fig. 2 is a bottom view, on a larger scale, of the base shown in Fig. 1, the base being removed from the candle;

Fig. 3 is a bottom plan view of a candle provided with a base of a somewhat modified form;

Fig. 4 is an end view of the base shown in Fig. 3;

Fig. 5 and Fig. 6 are bottom and end views, respectively, of a candle base in accordance with another form of the invention;

Fig. 7 and Fig. 8 are bottom and end views, respectively, of candle bases made in accordance with yet another form of the invention;

Fig. 9 and Fig. 10 are bottom and end views, 55

respectively, of candle bases, illustrating a further form of the invention;

Figs. 11 and 12 are bottom and end views, respectively, of candle bases showing a further modification.

Referring now to the drawing in detail and first to the form of the invention illustrated in Figs. 1 and 2, the candle C, is, as usual, disposed within a holder H of glass or other suitable material. Said holder tapers downwardly and is slightly larger in diameter than the candle to provide, as usual, a peripheral space S between the inner surface of the holder and the outer surface of the body of the candle. The wick 10 W which extends upwardly through the central opening O in the body of the candle and fits somewhat loosely therein is attached to the bottom of the candle by the base 10 embodying the present invention. Said base comprises a disk of thin sheet metal having a plurality of downwardly struck out prongs 12 providing an opening 14 through which the lower end portion WL of the wick W extends, said portion of the wick being engaged between adjacent prongs 12 and thereby secured to the base. Said base is provided with upwardly extending corner prongs 16 which penetrate the body of the candle adjacent the bottom thereof for attaching the base to the candle. In order to prevent the candle from tilting, base 20 10 is provided with means here shown with a plurality of downwardly pressed projections 18, here shown as circular ribs, which extend beyond the prongs 12 downwardly in a direction axially of the candle. It will be observed that 30 the means for preventing tilting of the candle are formed integral with the disk of the metal base and are positioned sufficiently close to the lower peripheral end of the candle, whereby to hold the candle in upright position at all times.

As will presently appear, the bases can be of various shapes and sizes and the means for preventing the tilting of the candle can assume various forms. Thus, for example, as illustrated in Figs. 3 and 4, the base 10a is substantially the same as the base 10 except that the means for preventing tilting are constituted by projections or tongues 18a which are partly struck out from the sheet metal disk of the base to provide openings for the passage of melted wax from the bottom of the disk to the top thereof. As shown in Fig. 5, the base is a circular disk having a continuous circular periphery which may be of the same diameter as the diameter of the candle at the lower end thereof. Said base 10b has upwardly extending prongs 16b for secur-

ing the base to the candle. As here shown, said base 10b is provided with projections 18b which are similar to the projections 18a of disk 10a, said projection 18b being partially struck out from the body of the disk. As shown in Fig. 7, the base 10c is constituted by a disk of non-circular configuration and is provided with outwardly pressed projections or circular ribs 18c like the projections 18 of base 10. The prongs 16c are struck out upwardly from the disk of base 10c for securing the latter to the bottom of the candle.

As illustrated in Figs. 9 to 12, the means for preventing tilting of the candle can be constituted by elongated pressed out elements or non-circular ribs 18d in the case of the base 10d illustrated in Figs. 9 and 10, or can be constituted by a single peripheral downwardly pressed circular rib 18e, as on the base 10e shown in Figs. 11 and 12. Bases 10d and 10e are provided with corner prongs 16d and 16e, respectively, for securing said bases to their respective candles.

Thus, it is seen that the candle bases herein shown or described are well adapted to accomplish the main and ancillary objects of the invention. More particularly, it will be observed that the bases are provided with the downwardly pressed prongs for securing the wick against upward movement in the candle body and at the same time the candle is prevented from tilting, inasmuch as the projection or projections on the bases of the candles extend below the wick holding tongues. It will be understood, however, that while I have shown and described several forms of the invention, the invention is susceptible of numerous other embodiments, and that various changes can be made in each of the illustrated embodiments. Accordingly, I do not wish to be limited to the invention as herein shown or described or to any of the specific forms herein disclosed, except as may be required by the scope of the appended claims.

Having thus described my invention, what I claim and desire to secure by Letters Patent is:

1. A base for a candle having a wick passing upwardly through the candle from the bottom

thereof, said base comprising a sheet metal disk having an opening through which the lower end of the wick projects and downwardly projecting struck out tongues for engaging said end of the wick to hold the latter against movement upwardly through the candle, said tongues extending below the plane of said disk, and means pressed downwardly from said disk to prevent tilting of the candle carried by the base due to the extension therebelow of said wick-securing tongues.

2. A base for a candle having a wick passing upwardly through the candle from the bottom thereof, said base comprising a disk having an opening through which the lower end of the wick projects, means projecting upwardly from the base at the periphery thereof for securing the base to the candle, and means projecting downwardly from the disk for securing said end of the wick to the base, said securing means extending below the plane of said disk, and means carried by said disk for preventing tilting of the candle mounted on the base due to the extension therebelow of said wick-securing means, said last mentioned means comprising a plurality of projections integral with the disk and projecting downwardly therefrom beyond said wick securing means.

3. A base for a candle having a wick passing upwardly through the candle from the bottom thereof, said base comprising a sheet metal disk having an opening through which the lower end of the wick projects and downwardly projecting struck out tongues for engaging said end of the wick to hold the latter against movement upwardly through the candle, said tongues extending below the plane of said disk, and a plurality of members pressed downwardly from said disk to prevent tilting of the candle carried by the base due to the extension therebelow of said wick-securing tongues, said downwardly pressed members having openings therethrough for the passage of melted wax from the bottom of the disk to the top thereof.

JOSEPH GISOLFI.
